CLAIM

The ornamental design for a cylindrical one-to-one
force-balance fluid pressure sensor component, as
shown.

DESCRIPTION

FIG. 1 is a front and top right perspective view of a
cylindrical one-to-one force-balance fluid pressure sen-
sor component showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof.
